UNITED STATES PATENT OFFICE.

SIGMUND L. GOLDMAN, OF CHICAGO, ILLINOIS.

BOTTLE COVER.

Application filed December 1, 1922. Serial No. 604,237.

To all whom it may concern:

Be it known that I, SIGMUND L. GOLDMAN, a citizen of the United States, residing at Chicago, in the county of Cook and State of Illinois, have invented a new and useful Improvement in Bottle Covers, of which the following is a specification.

My invention relates, more particularly, to covers for milk bottles, provided for the purpose of closing the mouths of bottles and adapted to be manipulated into a condition to permit of the pouring of the contents from the bottle.

My objects, generally stated, are to provide a novel, simple and inexpensive construction of cover which will operate to perform the functions above stated, in a highly efficient and desirable manner. More specifically certain of my objects are to provide a construction of cover which may be applied with ease to bottles, such as milk bottles, of different sizes; to provide for the conditioning of the cover device to provide a fluid outlet opening and an air vent, preferably by the adjusting of a single part of the cover, to facilitate the ready pouring of the contents out of the bottle; another object is to provide a construction the parts of which may be readily disassembled for cleansing and readily re-assembled into the proper relative positions, the parts being readily cleansable to render the structure highly sanitary; and other objects as will be manifest from the following description.

Referring to the accompanying drawings:

Figure 1 is a plan view of my improved bottle cover showing it as applied to a milk bottle, the shutter device thereof being shown in open condition. Figure 2 is a similar view showing the shutter device in closed position. Figure 3 is a view in elevation of the structure shown in Fig. 1, the lower portion of the bottle being broken away. Figure 4 is a section taken at the line 4-4 on Fig. 1 and viewed in the direction of the arrows. Figure 5 is a plan view of the spring device forming a part of the cover. Figure 6 is a plan view of the shutter device. Figure 7 is a plan view of the body, or plate, portion of the cover; and Figure 8, a view in elevation of a stud forming a part of the cover device.

The cover device as shown comprises a plate-like member of general disk-form, represented at 9, this member being prefer-

ably stamped from any suitable metal as, for example, aluminum, to present an annular groove 10 on its under side, at the circumference of the member 9, and a depressed central portion 11 on its upper surface which affords the circular recess 12, the bottom wall of this recess being centrally apertured as indicated at 13 and containing at diametrically disposed points, a circular opening 14 and an arc-shaped slot 15. The member 9 adjacent its circumferential margin, is provided with two pair of projections 16 located at diametrically-opposed points and preferably formed by striking up the metal of the member 9, these projections being positioned as shown in Fig. 7. The portion 9 of the cover device and which constitutes the body portion thereof, is provided for application to the mouth of a bottle as, for example, that shown at 17, to extend entirely across it, and is provided at its under side where it contacts the wall of the mouth, with a washer 18 which is located within the annular groove 10, this washer being constructed of any suitable material preferably a material which will not be acted upon by the casein contained in the milk where the cover device is used as a cover for a milk bottle. A suitable material for this purpose is rubber which has been treated, as is well understood in the art, to render it not subject to the deleterious action of casein. If desired, the washer 18 may be secured in the groove 10 in any desirable way, as, for instance, by cementing it therein by the use of white shellac.

The cover device also comprises a shutter shown as in the form of a circular disk 19 which extends within the recess 12. This shutter is centrally apertured, as represented at 20, the portion of the disk surrounding this aperture being upwardly deflected, as represented at 21, to form a hollow boss. The disk 19 also contains diametrically-opposed openings 22 and 23, the opening 22 being shown as circular, and the opening 23 of elongated form. The opening 22 which is adapted to cooperate with the opening 14 in the cover section 9 is preferably of slightly larger size than the opening 14, as shown, the opening 23, which is adapted to cooperate with the opening 15, being preferably of the same shape and size as the latter. The shutter device 19 is also shown as provided with an upwardly-ex-

tending lug 24 preferably formed integrally with the disk 19, as for example by stamping the disk with a radially-extending tongue thereon and thereafter turning up 5 this tongue to form the lug.

The cover device also comprises a spring device shown as formed of a single strip of spring metal, this spring device being represented at 25 and extending across the 10 top of the cover section 9 and the shutter 19 and located between the pairs of projections 16 as shown. The spring device 25 is of considerably greater length than the diameter of the cover section 9 and its depending 15 extremities, represented at 26, converge downwardly and terminate in bead portions 27, as shown in Fig. 3. The spring device 25 is centrally apertured, as represented at 28.

20 The cover section 9, shutter 19 and spring device 25, are held together by means of a fastening device comprising a stud 29 secured in the opening 13 in the section 9 and extending upwardly therefrom and presenting the threaded portion 30, and a wing-nut 31 which screws upon this threaded portion. The stud shown is formed at its lower end with a reduced portion 32 at which it fits in the opening 13, its lower 25 extremity being upset, as represented at 33, against the under side of the section 9, for the purpose of securing the stud in place. The stud, at the portion thereof above its reduced portion 32, extends 30 through the opening 20 in the shutter 19. The threaded portion 30 of the stud is of reduced diameter whereby an annular shoulder 34 is provided, the stud 29 extending at its threaded portion referred to 35 through the opening 28 in the spring device 25. The wing-nut 31 upon being tightened clamps the spring device 25 between it and the shoulder 34, the parts described being preferably so proportioned that the 40 shutter 19 may be rotated about the stud 29 with the desired ease.

The parts of the cover device may be 45 constructed of any desired material, it being preferred that the washer 18 be of such material that the casein of the milk will not deleteriously affect it, the other parts of the construction, excepting the spring device 25, being made of aluminum.

50 The cover device is adapted, with its parts assembled as shown in the drawings, to be applied to operative position on a bottle, as for example the milk bottle 17, as by sliding the cover device sideways over the mouth of the bottle, the beads 27 of the 55 spring device becoming interlocked with the reduced portion of the bottle neck as shown in Fig. 3, thereby firmly holding the cover device in a position in which it extends across the mouth of the bottle. When 60 the shutter device is in the position shown 65

in Fig. 2 the openings therein are out of registration with the openings 14 and 15 in which position the cover is closed. When it is desired to pour out the contents of the 70 bottle, the shutter device is rotated to the position shown in Fig. 1 in which position the openings 22 and 23 register with the openings 14 and 15 respectively, the 75 openings 23 and 15 serving as the outlet for the contents of the bottle, and the openings 14 and 22 serving as an air vent permitting of the even flow of the fluid from the bottle.

The parts of the structure are preferably 80 so constructed and arranged, as shown, that the spring device 25 forms an abutment for the lug 24 and when this lug engages this spring device as shown in Fig. 1 the cover is rendered open as explained.

85 One of the advantages of my construction is that it may be readily cleansed, this being accomplished by unscrewing the wing-nut 31 whereupon the parts 9, 19 and 25 may be separated and independently 90 cleansed as for example, by immersing them in boiling water, it being noted that the stud and wing-nut constitute a single unitary means for holding these various parts together in operative relation.

95 The purpose of the projections 16 on the cover section 9 is to insure the so-positioning of the spring device 25 that the openings in the shutter and the cooperating 100 openings in the section 9 will register, when the lug 24 in the rotation of the shutter device in one direction, abuts the spring device.

105 It will be understood that by forming the cover device as described it is adapted to be applied to bottles of different sizes as, for example, in the case of milk or cream bottles, to splits, pints or quarts.

110 While I have illustrated and described a particular construction embodying my invention, I do not wish to be understood as intending to limit it thereto as the same may be variously modified and altered without departing from the spirit of the invention.

115 What I claim as new, and desire to secure by Letters Patent, is:

120 1. A cover device comprising a plate-portion adapted to extend across the mouth of a bottle, a spring device extending across the upper surface of said plate-portion and presenting depending free springy portions which extend below the plane of the under surface of said plate-portion at opposite sides of the latter, said plate-portion being apertured, a shutter cooperating with the apertured portion of said plate-portion and provided with a projection cooperating with the spring to form a stop for limiting the movement of the shutter, projections on 125 said plate-portion for cooperation with said spring in the application of the latter to 130

said plate-portion and so related to the latter and to said shutter that when the latter is moved to a position in which the projection thereon engages said spring in one position of the shutter, a discharge opening for the contents of the bottle to which the device is applied is afforded, and means for holding said spring device in place.

2. A cover device comprising a plate-portion containing an aperture, a rotatable shutter controlling said aperture, a spring device for attaching the cover to a bottle, and a single device securing all of said parts together and formed of releasable members adapting said parts to be disengaged from each other by disconnecting said members.

3. A cover device comprising a plate-portion adapted to extend across the mouth of a bottle, said plate-portion being formed on its upper surface at its central portion with a depression and presenting an annular groove on its under side, said plate-portion being provided with upwardly-extending projections, the bottom of said depression containing an outlet aperture and

an air vent, a washer in said groove, a shutter located in said depression and containing an air vent opening and a fluid outlet so arranged that in one position of said shutter the openings in the latter register with the corresponding openings in said plate-portion, said shutter being provided with an upwardly-extending lug and containing a stud-receiving aperture, a spring device extending across the upper surface of said plate-portion and said shutter and provided with depending end portions at which it is adapted to be clamped upon the neck of a bottle, said spring device being located between projections on said plate-portion and forming a stop for the lug on said shutter in which position the apertures in said shutter register with the apertures in said plate-portion, a threaded stud extending through said shutter and spring device and engaging said plate-portion, and a nut screwing on the threaded portion of said stud for clamping the parts of the cover device together.

SIGMUND L. GOLDMAN.
